UNITED STATES PATENT OFFICE.

CHARLES A. STUART, OF KENOSHA, WISCONSIN, ASSIGNOR TO SIMMONS COMPANY, OF KENOSHA, WISCONSIN, A CORPORATION OF DELAWARE.

DESIGN FOR A GRILLE FOR BEDSTEAD FRAMES.

Application filed March 14, 1921. Serial No. 452,343. Term of patent 14 years.

To all whom it may concern:

Be it known that I, CHARLES A. STUART, a citizen of the United States, residing at Kenosha, in the county of Kenosha and State of Wisconsin, have invented a new, original, and ornamental Design for a Grille for Bedstead Frames, of which the following is a specification, reference being

had to the accompanying drawing, forming part thereof.

The drawing is an elevation of a grille showing my new design.

I claim:

The ornamental design for a grille for bedstead frames, as shown.

CHARLES A. STUART.
